[57]

CLAIM

The ornamental design of a spring for magnetic head, as shown.

DESCRIPTION

FIG. 1 is a front elevational view of spring for magnetic head showing our new design. The rear view is identical with the front view;

FIG. 2 is a top plan view thereof;

FIG. 3 is a left side elevational view thereof. The right side view is symmetrical with the left side view;

FIG. 4 is a bottom plan view thereof; and,

FIG. 5 is a perspective view thereof.

FIG.1

FIG.2
